UNITED STATES PATENT OFFICE

CHARLES KRESS CHERRY, OF LITTLE ROCK, ARKANSAS

VENDING MACHINE

Application filed October 18, 1927. Serial No. 226,964.

This invention relates to certain improvements in vending machines and it is an object of the invention to provide a machine of this kind operating to dispense or deliver a cup 5 of water.

It is also an object of the invention to provide a machine of this kind embodying a mechanism whereby a cup may be filled without accompanying delivery of another cup.

10 Another object of the invention is to provide a machine of this kind embodying a supply of cups together with a source of water supply and wherein means are provided under control of a single operating element 15 to effect the filling of a single cup from said source of water supply and delivering said filled cup to a consumer.

The invention consists in the details of construction and in the combination and arrangement of the several parts of my improved vending machines whereby certain important advantages are attained and the device rendered simpler, less expensive and otherwise more convenient and advantageous for 25 use, as will be hereinafter more fully set forth.

The novel feature of my invention will hereinafter be definitely claimed.

In order that my invention may be the 30 better understood, I will now proceed to describe the same with reference to the accompanying drawings, wherein:—

Figure 1 is a view partly in elevation and partly in section of a vending machine constructed in accordance with an embodiment 35 of my invention;

Figure 2 is a vertical sectional view taken substantially on the line 2—2 of Figure 1;

Figure 3 is a horizontal sectional view 40 taken through the lower portion of the machine with certain of the parts in top plan;

Figure 4 is an enlarged fragmentary view 45 partly in section and partly in elevation illustrating a portion of the operating mechanism as herein employed;

Figure 5 is a fragmentary view partly in section and partly in side elevation of the structure as illustrated in Figure 4;

Figure 6 is a fragmentary view partly in 50 top plan and partly in section illustrating the

holding dog or member associated with the cup stack;

Figure 7 is a view partly in elevation and partly in vertical section of the structure as 55 illustrated in Figure 6;

Figure 8 is a fragmentary view in top plan of the cup holding member as herein employed.

As disclosed in the accompanying drawings, C denotes a cabinet of any desired type 60 in the upper portion of which is arranged a vertically disposed cylindrical member 1 open at its lower end and constituting a magazine to contain an initial supply or stack of drinking cups D. The upper end of the member 1 opens through the top wall of the cabinet C and is continued by an upstanding magazine section 2 the walls of which being preferably of glass or the like with its upper end closed. This magazine section 2 permits ready visual 70 access within the magazine in order to determine when a refill is necessary and said magazine section 2 may be readily removed when it is desired to refill the magazine.

The lower portion of the member 1 is provided with a horizontally disposed slot or opening 3 through which extends a holding member 4, the inserted end portion of which being provided with the oppositely disposed curved arms 5 whereby said member 4 may 80 effectively engage the flange or bit 6 at the upper portion of the lowermost cup D within the member 1. The outer end portion of the member 4 is hingedly connected, as at 7, with a vertically disposed elongated block 8. The 85 intermediate portion of the block 8 is hingedly connected, as at 9, with an outstanding bracket 10 carried by the member 1 while in contact with the lower portion of the block 8 is a relief spring 11, said spring having one 90 end portion secured to the member 1. This spring 11 forces the lower portion of the block 8 outwardly and the upper portion inwardly thereof normally maintaining the holding member 4 in operative engagement with the 95 lowermost cup of the stack.

The outer portion of the member 4 has disposed transversely thereof a channel track 12 in which is received a depending lug 14 carried by an end portion of a holding dog 100

15. This dog 15 at a desired point intermediate its ends is pivotally held, as at 16, by an outstanding bracket 17 carried by the member 1. This dog 15 is disposed on desired curvature so that the end portion thereof remote from the member 4 readily passes into the member 1 through an opening 18 to engage below the flange or bit of the lowermost cup when the member 4 is moved outwardly 70 to release the lowermost cup. When the member 4 is again moved inwardly the dog 15 will be freed from the stack permitting the same to drop down until held by the member 4.

15 The lower portion of the cabinet C has in its front face a delivery opening 19 for a filled cup D, approach to such opening being over a series of rollers 20 upon which a cup D is adapted to travel. Below the rollers 20 is a 20 tray 21 for collecting such water as may be spilled and leading from the lower portion of the tray 21 is a carry-off pipe 22.

The lower portion of the cabinet C is provided to one side of the member 1 with a partition wall 23, said wall extending from the bottom wall 24 of the cabinet to a point slightly above the lower portion of the member 1. This partition wall 23 is provided with a pair of vertically spaced and 25 horizontally disposed trackways 25 with which are operatively engaged the flanges or shoes 26 extending outwardly from the side wall of a sliding carriage S. The bottom wall 28 of the carriage S engages a track- 30 way 29 disposed horizontally along a side wall 30 of the cabinet C. This sliding carriage S is adapted to be moved forwardly and rearwardly with respect to the tubular member 1 and is normally positioned directly 35 below said member 1 to receive the lowermost cup D when dropped from said member.

The carriage S in addition to the side wall 27 is provided with an upstanding rear wall 31. Projecting rearwardly from the upper 40 portion of this rear wall 31 at substantially the transverse center thereof is a bracket 32, to which is operatively connected, as at 33, an end portion of an elongated lever 34. This lever 34 extends rearwardly and laterally 45 with respect to the member 1 and has its central portion pivotally connected, as at 35, with an outstanding bracket 36 carried by the upper portion of the partition wall 23. This lever 34 extends beyond the opposite side of

50 the partition wall 23 through an opening 37 therein. The outer extremity of the lever 34, or that end portion thereof remote from the bracket 32, has operatively engaged therewith a retractile spring 38 also anchored to the rear wall 39 of the cabinet. This spring 38 is of sufficient tension to exert sufficient pull on the lever 34 to maintain the sliding carriage S in its normal position below the member 1.

The outer end portion of the lever 34 also 55 has operatively engaged therewith an end

portion of an elongated rigid member or rod 40 supported for sliding movement by the bearing members 41 extending from the partition wall 23, endwise movement of the member or rod 40 operating to effect requisite swinging movement of the lever 34. The forward end portion of the member of rod 40 has pivotally connected therewith, as at 42, an end portion of a pitman 43 which in turn is operatively engaged, as at 44, with a rotary operating member or wheel 45. This member or wheel 45 is adapted to be rotated to an extent sufficiently to effect a stroke of the member or rod 40 of a length sufficient to assure the requisite functioning of the machine. As herein disclosed, the periphery of the rotary member or wheel 45 is provided with an outstanding operating member or finger piece 46 projecting exteriorly of the casing through a vertically disposed slot 47 provided in the upper portion of the front wall of the casing C.

Rearwardly of the member 1 and within the casing C is a faucet 48 of a push valve type, said faucet being in communication with a 90 suitable source of water supply located as preferred.

The rotary member or wheel 45 is adapted to be normally locked against turning movement by a suitable latching mechanism under 95 check control but as this in itself forms no particular part of the present invention it is not believed necessary that a detailed description and illustration thereof be given. It is to be understood that any preferred locking mechanism and check controlled mechanism 100 may be employed.

As is believed to be clearly understood, the faucet 48 is normally closed with the valve of the faucet being moved into open position upon inward movement of the normally extending valve stem 49. As herein disclosed, the faucet 48 has slidably mounted thereon a yoke 50 including an outer end member 51 overlying the outer end of the stem 49 whereby upon inward movement of the yoke 50 the stem 49 will be moved inwardly and the associated faucet valve adjusted to open position.

When a check controlled mechanism is employed the requisite coin is adapted to be inserted through the chute 52, the lower portion of the casing being provided with a coin box 53 for the collection of the coins being deposited.

In operation, upon upward pull being imposed upon the finger piece 46 the rotating member or wheel 45 turns a distance sufficient to move the sliding carriage S rearwardly a distance to bring the cup D thereon below the faucet 48. As the carriage S moves rearwardly, the lever 34 comes into contact with the finger 54 depending from the inner portion of the yoke 50 and as the lever 34 continues its movement, the yoke 50 will be moved inwardly of the faucet 48 a distance sufficient 130

to carry the stem 49 inwardly to move the valve of the faucet into open position. It is to be understood that this operation is such that the faucet is not opened until after the cup D on the carriage S is properly positioned below the discharge opening of the faucet. It is to be understood that prior to the turning of the member or wheel 45 no cup is carried by the carriage S. When the member or 10 wheel 45, and more particularly the pitman 43 associated therewith, is in normal position the pitman 43 is arranged directly above an outstanding wedge-like trigger member 55 so that upon initial downward movement of the 15 pitman 43 the same comes into contact with the trigger 55 resulting in the lower portion of the block 8 being forced inwardly toward the member 1 and the upper portion of the block 8 together with the member 4 swinging outwardly to release the lowermost cup D which will drop down upon the carriage S positioned below the member 1. During this 20 operation, as hereinbefore explained, the dog 15 will coat with the next succeeding cup 25 to hold the stack within the member 1. During this release of the lowermost cup there will, of course, be a slight rearward movement of the carriage S but not sufficient to interfere with the proper placement of the 30 released cup D thereon.

The bottom wall 28 of the carriage S is provided with an elongated opening or slot 56 disposed in the same general direction as the direction of travel of the carriage and this 35 opening or slot 56 is adapted to be closed by an elongated arm 57 pivotally connected at one end, as at 58, to the lower portion of the carriage S and provided at its opposite end with an upstanding finger or lug 59. When 40 the carriage S is in its normal position below the member 1 the arm 57, as illustrated in Figure 2, drops down and rests upon an inclined or cam end portion 60 of an elongated member or cleat 61 mounted upon the bottom 45 wall 24 of the casing C. As the carriage S moves rearwardly, the arm 57 as it passes over the inclined portion 60 of the member or cleat 61 will swing upwardly bringing the lug 59 above the bottom wall 28 of the carriage S and 50 in advance of the cup D whereby it is positively assured that said cup will be carried rearwardly with the carriage.

After the member or wheel 45 has been turned by the person as far as it will go he 55 releases the same and the requisite reverse movements of the various parts will be accomplished through the medium of the spring 38. During this reverse movement the carriage S with the filled cup D thereon will 60 move forwardly to its normal position, prior to which the arm 57 will drop to remove any hindrance or obstruction being offered to the cup by the lug 59. During the returned movement of the member or wheel 45 and the pitman 43, the pitman 43 will contact from be-

low with the wedge-like trigger 55 and cause the same to slide upwardly and inwardly with respect to the block 8, thus permitting the pitman 43 on its returned movement to readily pass the trigger 55 without effecting the release of a cup D.

In order to prevent slamming of the various movable parts on the return movements thereof, I find it of advantage to provide a suitable checking medium which, as herein disclosed, comprises a conventional type of dash pot 62, the piston rod 63 comprised therein being operatively engaged with the lever 34 as is particularly illustrated in Figures 3 and 4 of the accompanying drawings.

The side wall 30 of the casing C with which the carriage S coacts is provided with a suitable opening 64 whereby a person may readily and conveniently apply a cup beneath the faucet 48 without operating the member or 85 wheel 45. When a cup is so positioned pull is imposed upon a rod 65 arranged within the casing C and having one end portion extending exteriorly of the casing through the front wall thereof. The inner or inserted end portion of the rod 65 is operatively connected, as at 66, with a lever 67. This lever 67 substantially midway its ends is supported, as at 68, for swinging movement upon an outstanding bracket 69 carried by the partition wall 23. 90 The opposite or outer end portion of the lever 67 is operatively connected, as at 70, with the yoke 50 whereby pull imposed upon the rod 65 causes the yoke 50 to move inwardly and 95 move the faucet valve to open position.

From the foregoing description it is thought to be obvious that a vending machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A vending apparatus of the class described comprising a cup magazine adapted to house a stack of cups, a normally closed faucet in communication with a source of water supply, a slidable carriage, means for reciprocating the carriage and normally maintaining the carriage below the magazine to receive a cup as dropped therefrom, and means operable upon movement of the carriage in a direction away from the magazine to open the valve of the faucet, and means for holding the cup upon the carriage during a reciprocable movement of the carriage, said means being inoperative when the carriage is in its normal position.

2. A vending apparatus of the class described comprising a cup magazine adapted to house a stack of cups, a normally closed faucet in communication with a source of water supply, a slideable carriage, means for reciprocating the carriage and normally maintaining the carriage below the magazine to receive a cup as dropped therefrom, means operable upon movement of the carriage in a direction away from the magazine to open the valve of the faucet, and means for releasing a cup from the magazine to drop upon the carriage upon initial movement of the carriage.
3. A vending apparatus of the class described comprising a cup magazine adapted to house a stack of cups, a normally closed faucet in communication with a source of water supply, a slideable carriage, means for reciprocating the carriage and normally maintaining the carriage below the magazine to receive a cup as dropped therefrom, means operable upon movement of the carriage in a direction away from the magazine to open the valve of the faucet, and a separate means for opening the valve of the faucet independently of the first named means.
4. A vending apparatus of the class described comprising a cup magazine adapted to house a stack of cups, a normally closed faucet in communication with a source of water supply, a slideable carriage, means for reciprocating the carriage and normally maintaining the carriage below the magazine to receive a cup as dropped therefrom, and means operable upon movement of the carriage in a direction away from the magazine to open the valve of the faucet, the means for reciprocating the carriage in one direction being automatic.
5. A vending machine comprising a reciprocating carriage, a normally closed faucet in communication with a source of liquid supply, means operating upon movement of the carriage in one direction to open the faucet for discharge within a cup upon the carriage, means for reciprocating the carriage, and means for holding the cup upon the carriage during a reciprocable movement of the carriage, said means being inoperative when the carriage is in its normal position.
6. A vending machine comprising a reciprocating carriage, a normally closed faucet in communication with a source of liquid supply, means operating upon movement of the carriage in one direction to open the faucet for discharge within a cup upon the carriage, means for reciprocating the carriage, said means for reciprocating the carriage being manually operated to move the carriage in one direction, the means for moving the carriage in the opposite direction being automatic, and means for holding the cup upon the carriage during a reciprocable movement of the carriage.

riage, said means being inoperative when the carriage is in its normal position.

7. A vending machine comprising a reciprocating carriage, a normally closed faucet in communication with a source of liquid supply, means for reciprocating the carriage, means operating upon movement of the carriage in one direction to open the faucet for discharge within a cup upon the carriage, said carriage having a bottom wall provided with an opening, an elongated arm pivotally connected to the carriage and having an upstanding finger adapted to extend above the bottom wall of the carriage through the opening therein, said arm normally swinging downward to maintain the finger below the bottom wall of the carriage, and fixed member with which the arm contacts upon reciprocation of the carriage to maintain the finger of the arm above the bottom wall of the carriage to maintain the cup upon the carriage.

8. A vending machine comprising a reciprocating carriage, a normally closed faucet in communication with a source of liquid supply, means operating upon movement of the carriage in one direction to open the faucet for discharge within a cup upon the carriage, means for reciprocating the carriage, said means for reciprocating the carriage being manually operated to move the carriage in one direction, the means for moving the carriage in the opposite direction being automatic, and means for retarding said second movement of the carriage.

In testimony whereof I hereunto affix my signature.

CHARLES KRESS CHERRY.
